[57] ABSTRACT

A movable space divider panel supported from an overhead track arrangement includes a bottom edge seal capable of moving upwardly or downwardly relative to the panel body to accommodate for any local unevenness in the floor thereby to maintain an effective sound barrier between the bottom of the panel and the floor surface at all times. The seal is supported on the floor by wheels or castors or a low friction slide arrangement. A body of foam is disposed between the panel body and the seal which acts to urge the seal towards the floor. The foam also acts as a sound insulator.

**BOTTOM EDGE SEAL FOR MOVABLE SPACE
DIVIDER PANELS**

INTRODUCTION

This invention relates to improvements of movable space divider structures of the type formed from a plurality of panels arranged for coplanar positioning, the panels being movable into a stacked storage position when the divider is not in use. 5

The panels of the movable space divider structures under consideration are supported by suitable means from an overhead track arrangement for movement therealong and the panels may or may not be hingedly interconnected one to another. When they are hingedly connected, the hinged connections may be between pairs of said panels; alternatively a continuous hinged arrangement of panels may be used wherein the panels are connected together in series at their edges by hinges. 10

Space dividers of the coplanar panel type are often referred to as operable walls in that they function to provide a movable wall section for space isolation purposes. Such structures must be capable of providing a relatively high sound transmission loss function since the primary purpose for using such structures is to provide proper sound insulation. With such structures an attempt is made to approach the sound insulating advantages of a fixed wall while retaining mobility. 15

BACKGROUND TO THE INVENTION

With the movable wall type divider being intended as a substitute for a fixed rigid wall construction, the mass and weight of the divider must be confined within limits permitting ready movement of the panels thereof into and out of operative space dividing relation. The prior art, in particular the structure shown in Canadian Pat. No. 761,743 of Charles R. Good et al. illustrates the construction of divider panels capable of providing adequate sound transmission loss characteristics in the speech privacy range while being sufficiently light in weight as to be readily movable by hand without the use of power operating means. The prior art also teaches that structural rigidity in movable panels is essential while at the same time acoustical "limpness" of the materials used is important to avoid "diaphragm" action in response to the impingement of sound vibrations thereon. 20

In addition to the problems of selective combination and fabrication of various materials in order to achieve the desired sound insulating properties, the establishing and maintaining of an efficient sound seal above, below and along the sides of each panel is essential to efficient use of a divider as a sound barrier. Peripheral leakage can make even the most efficient panel construction ineffective. Peripheral sealing arrangements cannot be unduly complex as ease of movement of the panels into and out of operative position is an important consideration of the effectiveness of a space divider of this type. Improved peripheral sealing arrangements are described in the above mentioned patent of Charles R. Good et al. This patent shows one form of device for helping to ensure an efficient sound seal between the panels when they are arranged in coplanar relation which includes means for forcing the panels into end engaging relation with one another longitudinally of the assembly thereby causing the panels to engage one another closely along their vertical margins. Since the 25

vertical margins of the panels are provided with resilient sealing or gasketing means, a relatively efficient sound transmission sealing effect between the panels is produced. 30

While the prior art provides quite efficient sealing arrangements for the vertical marginal edges of the panels, the sealing arrangements commonly provided along the bottom edges of the panels to provide sound barriers between the panels and the floor leave something to be desired. The most common form of bottom edge sealing arrangement includes elongated strips of flexible material secured to the lower edges of the panel in such a way that the strips bridge the gaps between the panels and the floor with the free lowermost edges of the strips contacting the floor surface. This arrangement functions reasonably well when the floor surface is perfectly level and uniform and perfectly parallel to the overhead track from which the panels are supported or suspended. However, these conditions are seldom encountered in practice. Most floors tend to be more or less uneven and in floors of large area, differences in floor elevation in the order of one or even a few inches are often encountered. Under such conditions, it is obvious that the simple bottom edge sealing arrangement described above is ineffective for its intended purpose. 35

THE INVENTION

30 The present invention, in one aspect, provides improved movable space divider panels each including a panel body portion adapted to be suspended from an overhead track arrangement and having a bottom edge sealing arrangement capable of moving upwardly or downwardly relative to the panel body and disposed adjacent the lower edge portions of the latter. As each panel body portion is moved along the overhead track from which it is suspended the sealing arrangement moves upwardly or downwardly to accommodate for any local unevenness of the floor thereby to maintain an effective sound barrier between the bottom of the panel and the floor surface at all times. The seal arrangement is provided with means for supporting the same on the floor so that the seal moves upwardly or downwardly in accordance with changes in the elevation of the floor while permitting ready movement of each panel over the floor. The seal support means may conveniently comprise wheels or casters to rollingly support the seal means on the floor; alternatively, a low-friction slide block arrangement may be used. In the preferred embodiment the sealing arrangement includes a body of resilient or spongy foam material which is interposed between the panel body and the 40 sealing arrangement which acts as a spring thereby to continually urge the sealing arrangement towards the floor to effect close engagement of the sealing arrangement therewith. The foam material also serves to act as a sound transmission barrier to further reduce sound 45 transmission between the panel body and the surface of the floor. 50

55 60

THE DRAWINGS

65 A fuller understanding of the invention will be had from the following description of a preferred embodiment of same wherein reference is made to drawings in which:

FIG. 1 is an elevation view of a movable space divider structure incorporating the features of the present invention;

FIG. 2 is a diagrammatic plan view of the structure of FIG. 1 with the stacked positions of the panels being shown in dotted lines;

FIG. 3 is a fragmentary elevation view of the lower left hand corner of one of the panels shown in FIG. 1 with portions of the panel cut away to show the interior structure;

FIG. 4 is a fragmentary sectional elevation view taken along line 4—4 in FIG. 1;

FIG. 5 is a plan section view of one end of the panel structure taken along line 5—5 in FIG. 4;

GENERAL ARRANGEMENT

FIG. 1 illustrates the movable space divider structure as comprising a plurality of flat panels 10 arranged as hingedly interconnected pairs disposed in coplanar relation. Each panel 10 is supported by a trolley assembly 14 suitably connected to a top portion of each panel, with the trolley assemblies riding on an overhead recessed track assembly 16 disposed within a ceiling structure 18 which serves to conceal the truck and trolley assemblies and through which each of the trolley assemblies 14 downwardly extend for interconnection to respective ones of each of the panels. Extending between the ceiling panel structure 18 and a floor structure 20 are fixed jamb posts 22 and 24 which define the opposing ends of the space within which the space divider is received thus completing the structure surrounding the divider structure.

FIG. 2 illustrates the divider structure in a partly folded position in full lines and in broken lines shows the stacking positions of the pairs of panels when the space divider is in its inoperative position. Suitable handles (not shown) may be provided on the panels 10 to facilitate their movement into the folded position as controlled by movement of their respective trolley assemblies 14 along track assembly 16.

Suitable devices may be provided to force the panels 10 into end engaging relation with one another longitudinally of the assembly when they are in co-planar relation with one another to cause the panels to engage one another closely along their vertical margins thus preventing sound leakage therebetween. Suitable devices for achieving this are disclosed in the above mentioned Charles R. Good patent.

GENERAL PANEL CONSTRUCTION

Each panel 10 comprises a body portion 26 and a bottom edge seal assembly 28 disposed at the bottom edge of each panel and arranged to bridge the gap which would exist, in the absence of seal assembly 28, between the lower edge of panel body 26 and the surface of floor 20.

The body portion of each panel is of generally conventional construction and includes a pair of spaced, parallel, co-extensive planar face plates 30, preferably of sheet steel, selected to provide acoustical "limpness" and structural rigidity. The outer faces of plates 30 are suitably coated to render same attractive in appearance. Rigidity is further assured by a marginal frame structure including vertically spaced upper and lower U-channel members 32 and 34 (see FIG. 4) and longitudinally spaced vertical U-channel members 36 extending the full height of the panel body (one of which is

shown in FIG. 5). Each of the above mentioned channel members is interposed between face plates 30 adjacent a respectively associated marginal edge of each face plate and is rigidly secured thereto by suitable fasteners (not shown). Frame members 32 and 34 are themselves fastened together at the four corners of the frame assembly by suitable brackets or by welding (not shown). The space between the face plates 30 is occupied by a glass fibre blanket 36 which acts to cut down sound transmission through the panel body 26. Panel body 26 is connected at its uppermost end to one of the trolleys 14 in conventional fashion and is suspended thereby in the manner well known in the art.

BOTTOM EDGE SEAL ASSEMBLY

Each bottom edge seal assembly 28, as seen in FIG. 1, extends the full length of the bottom edge of the panel body and is supported on the floor 20 by means of a spaced apart pair of swivel casters 38. The casters 38 are normally hidden from view, but in FIGS. 1 and 3 part of the structure has been cut away to expose them. Casters 38 permit freedom of movement of the panels across the floor surface and also prevent damage to the finished surface of same as the panels are moved along the overhead support track 16, while at the same time the casters and their associated seal assemblies move upwardly and downwardly relative to their associated panel bodies in response to local unevenness in the floor and/or lack of parallelism between the floor and the overhead track 16. Local unevenness in floor 20 is illustrated, in somewhat exaggerated form, in FIG. 1. Each seal assembly 28, as seen in FIG. 4, (which is a section view normal to the longitudinal axis of the panel) includes a generally U-shaped-in-cross-section shell 40 including a base 42 and a spaced pair of flanges 43 connected thereto and extending upwardly for a short distance in closely spaced overlapping or telescoping relation to the lower portions of face plates 30 of panel body 26 such that shell 40, in effect, embraces the entire bottom edge portion of its associated panel body. The inwardly facing surface of each flange 43 is shown as covered with a sheet of chipboard or pressed wood 44 for sound isolation purposes while the outwardly facing surfaces of same are provided with a suitable covering or coating so as to render the same attractive in appearance.

In order to accommodate the casters 38, suitably spaced apertures are provided in the base 42 of shell 40. Caster mounting brackets 46 are secured to base 42 as shown in FIG. 3 and are shaped to provide recesses in the bottom of shell 40 within which the casters are partially disposed, with casters 38, in turn, being each secured to a respective one of the brackets. Each bracket being of a generally inverted U-shaped configuration, permits the lowermost portions of shell 40 to be disposed quite close to the surface of floor 20 thus further reducing the amount of sound transmitted therebetween while permitting casters 38 to be of a reasonable and adequate size to bear the loads encountered during use.

In order to guide the shell 40 and its associated structure upwardly or downwardly relative to panel body 26, a pair of spaced guide members 48 are provided, each connected to a respective one of the opposing end portions of shell 40 at the base 42 of the latter by rivets 51 or the like and extending vertically upwardly in juxtaposition to and sliding relation with an associated one

of the vertically disposed U-channel marginal frame members 34 as best seen in FIGS. 4 and 5. Each guide member 48 is preferably of U-channel cross section to provide the necessary rigidity, and is dimensioned so as to have a free sliding fit within the outwardly facing groove defined by each of the vertical U-channel frame members 34. Guide members 48 each have an elongated slot 50 formed therein which co-operates with an associated stop screw 52 passing through the slot and threaded into its associated vertical frame member 34. Guide members 48 therefore, in co-operation with vertical frame members 34, guide the shell assembly 40 upwardly or downwardly between fixed limits determined by slot 50 and pin 52 relative to the panel body 26 in a predetermined path of travel.

Disposed between the lower edge of panel body 26 as defined by lower channel member 32 and base 42 of the shell 40 of the bottom edge seal assembly is a body 54 of resilient plastic or rubber spongy foam material. Foam body 54 substantially fills the space existing between shell 40 and the lower edge of panel body 26 except, of course, that narrow clearance spaces are left to avoid undue friction between the foam and other parts of the assembly. The foam body serves two main functions; it further reduces sound transmission between the lower edge of the panel body, and it acts to resiliently urge the bottom edge seal assembly 28 towards the floor thereby ensuring that its casters 38 remain in contact with and follow the contours of the floor at all times. The foam body is selected such that the amount of force transmitted therethrough to shell 40 is relatively small at all times. If the foam body is too stiff and rigid an undesirably great amount of force may be transmitted therethrough which could overload the casters and damage same. In other words, the foam body is arranged such that most of the weight of panel body 26 is carried by the overhead track 18 with only a small portion of its weight being transmitted through the foam to shell 40 and casters 38.

In order to complete the bottom edge seal arrangement, a flexible floor engaging or "sweeper" seal 56 is affixed to each of the longitudinally extending lower edges of the shell 40 thereby to bridge the relatively small gap remaining between the latter and the floor surface. Each floor engaging seal 56 includes a support channel 58 suitably secured to shell 40 and a flexible seal 60 per se of any suitable cross-sectional configuration.

OTHER SEALING DEVICES

Sealing means are also provided along the top and on the vertical marginal edges of each complete panel 10 to provide an effective barrier against sound transmission. The top edge sealing means 60 is shown in FIG. 4 and comprises flexible finger seals 61 secured in suitable channels 62 disposed along the longitudinal edges of a panel top closure plate 64. The tips of finger seals 61 contact the previously mentioned ceiling structure 18 thereby reducing sound transmission between the latter and the top of the panel.

The opposing vertical edges defined by the ends of the shell 40 of the bottom edge seal 28 are also provided with flexible finger seals 66 secured in channel members suitably affixed to shell 40 (see FIGS. 3 and 5). When panels 10 are in end-to-end abutting relation with one another the finger seals 66 of the bottom end sealing devices come into contact with one another.

To complete the sealing arrangement, the opposing vertical marginal edges of each panel body 26 are provided with seals, a typical seal 68 being seen in FIG. 5. A seal 68 is provided on the trailing vertical edge of each panel 10, which seal includes an elongated member 70 extending the full height of the panel body and secured thereto. Member 70 defines a groove 72 adapted to receive a tongue of corresponding cross sectional shape (shown in dotted lines in FIG. 5) attached to the leading vertical edge of the panel body next adjacent thereto. Groove 72 has a pair of inwardly converging side walls 74 each having an elongated channel therein each carrying a flexible sealing strip 76 which extends the full length of its associated groove. Each strip 76 includes a pair of flexible lip portions 78 which extend into the central portion of the groove thereby to engage opposing sides of the tongue portion of the panel next adjacent thereto when the panels 10 are in co-planar end engaging relation. In this fashion, an effective sound barrier between the marginal edges of the panels is provided.

I claim:

1. A space divider panel of the type adapted to be supported over a floor surface from an overhead trolley and track arrangement and brought into end-engaging relation with another panel of the same or similar construction to provide a barrier against the transmission of sound from one region of a space to another, said panel comprising: a panel body portion of a sound insulating construction adapted to be suspended from an overhead trolley and track arrangement in a generally upright position, and a bottom edge seal means mounted to said panel body portion such that said seal means is disposed along that edge of the panel body portion which is lowermost when the panel is in its upright assembled position, the bottom edge seal means including means adapted to continually contact the floor surface and to continually support the bottom edge seal means on the floor while permitting freedom of movement of the panel over the floor when the panel is moved along the overhead track assembly, the bottom edge seal means being mounted to said panel body portion such that it is free to move up and down relative to the panel body portion in response to said floor surface contacting means encountering local unevenness in the floor and/or lack of parallelism between the floor surface and the support track used for supporting the panel body portion as said panel is moved along the overhead track arrangement with the bottom edge seal means being so constructed and being so related to the means for continually contacting the floor surface, that said bottom edge seal means continually bridges and forms a sound barrier across the gap that would exist, in the absence of the bottom edge seal, between said lowermost edge of the panel body and the surface of the floor during said movement of the panel along said overhead track assembly and means comprising a resilient elongated body of a sound absorbing or deadening material disposed between said panel body portion and the bottom edge seal means and extending substantially the full length of the bottom edge seal means to urge the latter towards the floor surface and to bring said floor contacting means into intimate engagement with the floor surface.
2. The structure according to claim 1 wherein said resilient body comprises a body of spongy sound insulating foam material.

3. The structure according to claim 1 wherein the means for continually contacting the floor surface comprises means to rollingly support said bottom edge seal means on the floor.

4. The structure according to claim 1 wherein the panel body is of generally planar configuration and includes opposing planar faces and wherein said bottom edge seal means includes portions extending in overlapping relation with respect to portions of said planar faces and freely movable with respect thereto thereby to assist in reducing sound transmission between said bottom edge seal means and the panel body portion.

5. The structure according to claim 2 wherein the panel body is of generally planar configuration and includes opposing planar faces and wherein said bottom edge seal means includes a shell of a generally U-shaped configuration as seen in a section view taken normal to the length of the seal means with the panel body arranged such that those portions of the latter which are lowermost when the panel is vertically disposed are over lapped and embraced by said shell, said body of spongy foam material being disposed between the lowermost edge of the panel body and a lower portion of the shell to form a sound insulating barrier therebetween.

6. The structure according to claim 2 wherein the bottom edge seal means includes means adapted to operate in telescoping relation with said edge of the panel body which is lowermost.

7. The structure according to claim 6 wherein the means for continually contacting the floor surface comprises means to rollingly support said bottom edge seal means on the floor.

8. The structure according to claim 8 wherein said bottom edge seal means includes a shell of a generally U-shaped configuration as seen in a section view taken normal to the length of the seal means with the panel body arranged such that those portions of the latter which are lowermost when the panel is vertically disposed are embraced by said shell, said body of material being disposed between the lowermost edge of the panel body and a lower portion of the shell to form a sound insulating barrier therebetween, said lower portion of the shell having recesses therein within which the rolling bottom edge seal support means are partially disposed thus permitting said shell to be disposed closely to the floor surface to reduce sound transmission therebetween and wherein said shell includes at least one flexible sealing strip connected thereto and extending longitudinally thereof and disposed for engagement with a floor surface whereby to bridge the remaining gap between the floor surface and the lowermost portions of the shell when the panel is in its upright assembled condition.

9. The structure according to claim 1 wherein the bottom edge seal means includes at least one flexible sealing strip connected thereto and extending longitudinally thereof and disposed for engagement with a floor surface when the panel is in its upright assembled condition.

10. The structure according to claim 1 wherein said bottom edge seal means includes guide means associated therewith, said panel body portion having means associated therewith receiving said guide means for up and down movement of the latter with respect thereto, and stop means associated with said guide means to define the limits of travel of the guide means and bottom

edge seal means with respect to the panel body portion.

11. The structure according to claim 1 wherein said panel body portion includes marginal frame members extending the height of the body portion, guide means connected to the bottom edge seal means and extending in juxtaposition to and sliding relation with associated ones of said frame members, and pin and slot means associated with the frame members and guide means for defining the limits of travel of the bottom edge seal with respect to the body portion.

12. The structure according to claim 2 wherein said panel body portion includes marginal frame members extending the height of the body portion, guide means connected to the bottom edge seal means and extending in juxtaposition to and sliding relation with associated ones of said frame members, and pin and slot means associated with the frame members and guide means for defining the limits of travel of the bottom edge seal with respect to the body portion, wherein the bottom edge seal means includes a shell of a generally U-shaped configuration as seen in a section view taken normal to the length of the seal means with the panel body arranged such that those portions of the latter which are lowermost when the panel is vertically disposed are embraced by said shell, with one each of said guide means being associated with a respective one of the opposing ends of said shell.

13. The structure according to claim 2 wherein sealing strips are disposed along the edges of the panel which come, in use, into end engaging relation with other panels thereby to reduce the transmission of sound therebetween.

14. The combination of an overhead track and trolley arrangement and a series of space divider panels vertically supported by said track and trolley arrangement, said panels adapted to be brought into end engaging relation with one another to provide a barrier against the transmission of sound from one region to another, at least a plurality of said panels each comprising a panel body portion of a sound insulating construction secured to and suspended from the track and trolley arrangement and a bottom edge seal means disposed along the lowermost edge portion of the panel body portion; the bottom edge seal means including means for continually contacting the floor surface and continuously supporting the bottom edge seal means on the floor while permitting freedom of movement of the panel over the floor as the panel is shifted along the overhead track assembly, the bottom edge seal means further being arranged such that it is free to move up and down relative to its associated panel body portion in response to the floor surface contacting means encountering unevenness in the floor and/or lack of parallelism between the floor surface and the overhead track arrangement, with the bottom edge seal means being so constructed and being so related to the means for continually contacting the floor surface that said bottom edge seal means continually bridges and forms a sound barrier across the gap that would exist, in the absence of the bottom edge seal, between said lowermost edge of the panel body and the surface of the floor during said movement of the panel along said overhead track assembly.

15. The structure according to claim 1 wherein the bottom edge seal means includes marginal frame members extending the height of the body portion, guide means connected to the bottom edge seal means and extending in juxtaposition to and sliding relation with associated ones of said frame members, and pin and slot means associated with the frame members and guide means for defining the limits of travel of the bottom edge seal with respect to the body portion, wherein the bottom edge seal means includes a shell of a generally U-shaped configuration as seen in a section view taken normal to the length of the seal means with the panel body arranged such that those portions of the latter which are lowermost when the panel is vertically disposed are embraced by said shell, with one each of said guide means being associated with a respective one of the opposing ends of said shell.

length of the bottom edge seal means to urge the latter towards the floor surface.

15. The structure according to claim 14 wherein said resilient body comprises spongy sound insulating foam material.

16. The structure according to claim 15 wherein the means for continually contacting the floor surface comprises means to rollingly support said bottom edge seal means on the floor.

17. The structure according to claim 14 wherein the panel body is of generally planar configuration and includes opposing planar faces and wherein said bottom edge seal means includes portions extending in overlapping relation with respect to portions of said planar faces and movable with respect thereto, said portions extending in overlapping relation having sound insulating material thereon thereby to reduce sound transmission between said bottom edge seal means and the panel body portion.

18. The structure according to claim 14 wherein the panel body is of generally planar configuration and includes opposing planar faces and wherein said bottom edge seal means includes a shell of a generally U-shaped configuration as seen in a section view taken normal to the length of the seal means with the panel body arranged such that those portions of the latter which are lowermost are overlapped and embraced by said shell said body of material being disposed between the lowermost edge of the panel body and a lower portion of the shell to form a sound insulating barrier therebetween.

19. The structure according to claim 15 wherein the bottom edge seal means includes means adapted to cooperate in telescoping relation with said edge of the panel body which is lowermost.

20. The structure according to claim 19 wherein the means for contacting the floor surface comprises means to rollingly support said bottom edge seal means on the floor.

21. The structure according to claim 20 wherein said bottom edge seal means includes a shell of a generally U-shaped configuration as seen in a section taken normal to the length of the seal means with the panel body arranged such that those portions of the latter which are lowermost are embraced by said shell, said body of spongy foam material being disposed between the lowermost edge of the panel body and a lower portion of the shell to form a sound insulating barrier therebetween, said lower portion of the shell having recesses therein within which the rolling bottom edge seal support means are partially disposed thus permitting said shell to be disposed closely to the floor surface to re-

duce sound transmission therebetween and wherein said shell includes at least one flexible sealing strip connected thereto and extending longitudinally thereof and disposed for engagement with a floor surface whereby to bridge the remaining gap between the floor surface and the lowermost portions of the shell when the panel is in its upright assembled condition.

22. The structure according to claim 14 wherein the bottom edge seal means includes at least one flexible sealing strip connected thereto and extending longitudinally thereof and disposed for engagement with the floor surface when the panel is in its upright assembled condition.

23. The structure according to claim 15 wherein said bottom edge seal means includes guide means associated therewith, said panel body portion having means associated therewith receiving said guide means for up and down movement of the latter with respect thereto, and stop means associated with said guide means to define the limits of travel of the guide means and bottom edge seal means with respect to the panel body portion.

24. The structure according to claim 14 wherein said panel body portion includes marginal frame members extending the height of the body portion, guide means connected to the bottom edge seal means and extending in juxtaposition to and sliding relation with associated ones of said frame members, and pin and slot means associated with the frame members and guide means for defining the limits of travel of the bottom edge seal with respect to the body portion.

25. The structure according to claim 15 wherein said panel body portion includes marginal frame members extending the height of the body portion, guide means connected to the bottom edge seal means and extending in juxtaposition to and sliding relation with associated ones of said frame members, and pin and slot means associated with the frame members and guide means for defining the limits of travel of the bottom edge seal with respect to the body portion, wherein the bottom edge seal means includes a shell of a generally U-shaped configuration as seen in a section taken normal to the length of the seal means with the panel body arranged such that those portions of the latter which are lowermost are embraced by said shell, with one each of said guide means being associated with a respective one of the opposing ends of said shell.

26. The structure according to claim 15 wherein sealing strips are disposed along the edges of the panel which come, in use, into end engaging relation with other panels thereby to reduce the transmission of sound therebetween.
